UNITED STATES PATENT OFFICE.

GEORGE A. WEBER, OF STAMFORD, CONNECTICUT, ASSIGNOR TO THE WEBER RAILWAY JOINT MANUFACTURING COMPANY, OF NEW YORK, N. Y., A CORPORATION OF WEST VIRGINIA.

RAILROAD-RAIL JOINT.

SPECIFICATION forming part of Letters Patent No. 739,463, dated September 22, 1903.

Application filed February 3, 1902. Serial No. 92,291. (No model.)

To all whom it may concern:

Be it known that I, GEORGE A. WEBER, a citizen of the United States, residing at Stamford, county of New Haven, and State of Connecticut, have invented certain new and useful Improvements in Railroad-Rail Joints, of which the following is a specification.

My invention relates to railroad-rail joints.

I will describe a railroad-rail joint embodying my invention and then point out the novel features thereof in the claims.

In the accompanying drawings, Figure 1 is a top plan view of a railroad-rail joint embodying my invention. Fig. 2 is a cross-sectional view. Fig. 3 is a cross-sectional view showing a different form of rail. Fig. 4 is a cross-sectional view and showing a modification.

Similar letters of reference designate corresponding parts in all of the figures.

A' A² designate two adjacent railroad-rail sections arranged in line to form a portion of a track.

B designates an angle-chair having a base b', an upright b², and an angle-brace b³. This angle-chair is long enough to receive the end portions of the two rail-sections A' A².

On one side of the rail-sections is a fish-plate C, preferably of the kind known as an "angle" fish-plate, having a flange c', adapted to bear upon the flange forming one side of the rail-sections, and an upright c², extending up to the under side of the heads of the rail-sections. This fish-plate will ordinarily be the same length as the angle-chair.

On the opposite side of the rail-sections is a fish-plate or channel-bar fitting snugly between the other flange comprised in the bases of the rail-sections and the opposite portion of the heads of the rail-sections. This fish-plate or channel-bar will ordinarily be of the same length as the fish-plate C.

Within the fish-plate or channel-bar D is a block E of packing material, preferably of wood. Bolts F' pass through the fish-plates C and D and webs of the rail-sections, the block of packing material E, and the upright of the chair B.

F designates a raiser-plate. This raiser-plate may be the same length as the angle-

chair B or shorter, in which case there would be a plurality of raiser-plates employed under each angle-chair. The raiser-plate F is provided with a supporting-face f, a base f', and preferably with lugs or flanges f², by means of which the raiser-plate may be secured to a railroad-tie. The supporting-face f is inclined, so as to cant or tilt the rail, and the angle-chair is retained thereon by flanges f⁴. The two tracks will therefore be tilted or canted toward each other.

f³ designates bolts or rivets which secure or hold the angle-chair and raiser-plate together.

In addition to the raiser-plate having the inclined supporting-face I may employ a cradle G. (See Fig. 4.) The cradle G rests on the base b' of the angle-chair and is particularly advantageous when bull-head rails are employed in the track. When a cradle G is employed, the height of the raiser-plate is reduced. The bolts or rivets f³ secure the cradle G, angle-chair B, and raiser-plate F together.

In Figs. 1 and 2 the form of rail employed is the usual T-rail. In Figs. 3 and 4 I have shown my invention in connection with a bull-head rail A³. When bull-head rails are employed, the flange c' preferably fits about the flange of the rail in the manner shown in the drawings.

While I have only shown provision for tilting or canting the rail-sections in the construction of the raiser-plate, yet it is my intention to cover all constructions which will be the obvious equivalents.

Having thus described my invention, the following is what I claim as new:

1. The combination with a railroad-rail joint comprising fish-plates and an angle-chair, a raiser-plate having an inclined supporting-face in which the rail-joint rests, and projections upon said raiser-plate for securing the face of the angle-chair in position thereon.

2. In a rail-joint, the combination with the rail-ends to be joined, of an angle-chair adapted to support the base of the joint and having an upright portion, a channel-bar spanning the joint and in contact therewith, and

a block of packing material fitted within the hollow of the channel-bar and resting against the upright, a fish-plate on the opposite side of the rail also spanning the joint between 5 the rail ends to be joined and bolts passing through both plates, the packing and the upright of the angle-chair, to secure the parts together.

3. A rail-joint, comprising a raiser-plate 10 having an inclined supporting-surface and retaining-flanges, an angle-chair supported upon the inclined surface of the raiser-plate and retained thereon by the said flanges, and fish-plates spanning the joint and secured to 15 the chair, for substantially the purposes set forth.

4. A rail-joint, comprising a raiser-plate having an inclined supporting-surface, an angle-chair supported thereon, means for securing 20 the raiser-plate and chair together, and fish-plates spanning the joint, for substantially the purposes set forth.

5. A rail-joint, comprising a raiser-plate having an inclined supporting-surface, an angle-chair supported thereon, a cradle for the 25 rails resting on the base of the angle-chair, and fish-plates spanning the joint and secured to the chair, for substantially the purposes set forth.

30 6. The combination with the meeting ends of rails, a suitable support for the same, and means for maintaining said rail ends in alignment, of a raiser-plate having an inclined supporting-surface for the said rail-support,

and means for securing the raiser-plate and 35 support, together, for substantially the purposes set forth.

7. The combination with the meeting ends 40 of rails, a suitable support for the same, and means for maintaining said rail ends in alignment, of a raiser-plate having an inclined supporting-surface, and a cradle for the rail-support resting upon the raiser-plate, for substantially the purposes set forth.

8. The combination with the meeting ends 45 of rails, a suitable support for the same, and means for maintaining said rail ends in alignment, of a raiser-plate having an inclined supporting-surface for the said rail-support, and means for securing the support-cradle 50 and raiser-plate together, for substantially the purposes set forth.

9. The combination with the meeting ends 55 of rails, a suitable support for the same, and means for maintaining said rail ends in alignment, of a raiser-plate having an inclined supporting-surface for the said rail-support, and retaining-flanges extending upwardly from the raiser-plate, for substantially the purposes set forth.

In testimony whereof I have signed my name to this specification in the presence of two subscribing witnesses.

GEORGE A. WEBER.
